US00D650102S

(12) **United States Design Patent**
Pearson

(10) **Patent No.:** US D650,102 S
(45) **Date of Patent:** ** Dec. 6, 2011

(54) **FLASHLIGHT**

(76) Inventor: **Arthur Scott Pearson**, Upland, CA
(US)

(**) Term: **14 Years**

(21) Appl. No.: **29/292,276**

(22) Filed: **Oct. 6, 2007**

(51) **LOC (9) Cl.** 26-02

(52) **U.S. Cl.** D26/38; D26/50

(58) **Field of Classification Search** D26/37,
D26/46, 48, 38, 51; 362/157, 158, 183, 184,
362/194-196, 200-208, 190, 191

See application file for complete search history.
